COMBINATION ARTICLE OF BABY FURNITURE

Ida E. Adams, Atlantic City, N. J.

Application February 11, 1949, Serial No. 75,844

5 Claims. (Cl. 155—123)

1

This invention relates to a combination item of baby furniture providing a combination high chair with feeding tray, a play table, swing and pot chair.

More particularly, it is an object of the present invention to provide a combination article of baby furniture also including a toy chest in which a number of toys may be stored in a convenient and accessible manner.

Another object of the invention is to provide an item of furniture having a chair provided with a removable seat portion for exposing a sub-bottom of the chair containing an opening forming a baby's toilet seat and having means for supporting a pot or receptacle detachably on the under side thereof and beneath said opening.

Another aim of the invention is to provide a combination including the seat which is normally supported for vertical yielding and substantially universal swinging movement in a horizontal plane relatively to its supporting structure and which seat may be readily connected to the supporting structure for maintaining it substantially rigid while employed as a toilet seat or for feeding an infant or young child.

Still another object of the invention is to provide an item of baby furniture including a high chair having a rigid tray not requiring raising or removal for applying a child to or removing it from the high chair.

Still a further object of the invention is to provide an item of furniture of the general nature heretofore described which is extremely compact yet very durable and efficient for its various intended purposes, which is attractive in appearance and sufficiently light to enable it to be readily moved from room to room and which will eliminate much of the bending and stooping required of mothers and nurses in attending to infants and young children in the use of a toilet seat or in feeding or tending to a child in a play pen.

Numerous other objects and advantages of the invention will hereinafter become more fully apparent from the following description of the drawings, illustrating a presently preferred embodiment thereof, and wherein:

Figure 1 is a front elevational view of the combination article of baby furniture;

Figure 2 is a side elevational view thereof looking from right to left of Figure 1;

Figure 3 is a rear elevational view thereof;

Figure 4 is a top plan view of the article of furniture;

Figure 5 is a vertical sectional view thereof taken substantially along a plane as indicated by the line 5—5 of Figure 4;

2

Figure 6 is a horizontal sectional view taken substantially along a plane as indicated by the line 6—6 of Figure 3;

Figure 7 is a transverse vertical sectional view taken substantially along a plane as indicated by the line 7—7 of Figure 5;

Figure 8 is a perspective view of one element of the invention, and

Figure 9 is a perspective view of another element thereof.

Referring more specifically to the drawings, the combination article of baby furniture in its entirety is designated generally 10 and includes a base, designated generally 11 composed of four corner blocks 12 which are connected by longitudinally extending bars 13 and transversely extending bars 14. Each of the corner blocks 12 is provided with a depending caster wheel 15 and said caster wheels provide a mobile support for the furniture item 10.

The furniture item 10 includes corresponding side walls 16 the lower end portions of which are suitably fastened to the sides of the base 11 and extend upwardly therefrom. The furniture item 10 is provided with a bottom 17 which is supported on and suitably secured to the base 11 and which extends between the sides 16 and from front to rear of the base 11. A horizontal partition 18 is disposed above and parallel to the bottom 17 and is supported by cleats 19 secured to the sides 16. As seen in Figure 1, the furniture item 10 is provided with a lower front wall 20 which is secured to and extends between the bottom 17 and partition 18 and also between the sides 16 to combine with said portions to form a chamber 21 preferably adapted for use as a toy chest the open rear end of which is partially closed and at the bottom thereof by a door or closure 22 which is hinged at one end thereof as seen at 23 to one of the sides 16 and which is provided with a conventional latch bolt 24 for releasably retaining the closure 22 in a closed position.

The side walls 16 are provided with complementary, relatively large openings 25 which extend from beneath and adjacent the level of the partition 18 to a point near the upper edges of said side walls. Said side walls 16 extend a substantial distance above the level of the partition 18 and are connected at their upper edges by a top wall 26 the forward edge of which is spaced rearwardly from the forward edges of the side walls 16, as best seen in Figure 5. Said side walls 16 are provided with rounded corners 27 at their upper, forward ends. The top wall 26 which forms a tray or table is provided with a recess

or notch 28, as best seen in Figure 4, which opens outwardly of the rear edge thereof and which diverges in width from its closed, forward end to its open, rear end. The tray 26 is provided with a guard rail 29 extending across the forward edge and along its side and which is supported by spaced posts 30.

The furniture item 10 is provided with an upper front wall 31 which extends between and is suitably secured to the side walls 16 and which is disposed above and spaced from the lower front wall 20 and terminates below the level of the tray 26. A foot rest 32 extends across the inner side of the front wall 31 adjacent its lower edge, as best seen in Figure 5, and is detachably supported on the side walls 16 by means of cleats 33.

A seat structure, designated generally 34 includes a bottom 35, which is removable, a sub-bottom 36 which is disposed therebeneath and which forms a stationary portion of the seat 34 and has corner posts 37 secured to and rising from the corners thereof. Said seat structure 34 also includes side bars 38 which extend upwardly from the side edges of the sub-bottom 36 and a front upright guard post 39 which rises from the forward edge and intermediate of the side edges of the sub-bottom 36. A guard railing 40 extends across the front and along the sides of the seat structure 34, as best illustrated in Figures 5 and 7 and is secured to the upper ends of the corner posts 37 and the posts or bars 38 and 39. The seat structure 34 also includes a back 41 which extends from adjacent the upper surface of the sub-bottom 36 to a point substantially above the level of the guard rail 40 and which has the lower portion of one side edge thereof swingably connected by hinges 42 to one of the rear corner posts 37 and which is provided adjacent its opposite side edge with a latch bolt 43 for detachably latching the back 41 to the other rear corner post 37 for releasably retaining it in a closed position, as illustrated in the drawings. It will be readily apparent that with the latch bolt 43 in a retracted position that the back 41 may be swung rearwardly on the hinges 42 to an open position, as illustrated in dotted lines in Figure 4 for exposing the rear of the seat structure 34 so that a child or infant can be inserted into the seat from the rear thereof and with the legs extending outwardly from the front of the seat structure 34 straddling the front post 39 and between the front corner posts 37 and the front guard rail portion, so that when the back 41 is thereafter latched in a closed position, the child will be retained in the seat structure 34 so that it cannot climb out or fall out or be removed until the back 41 is unlatched and again swung rearwardly and to an open position.

The sub-bottom 36 is provided with an opening 44, as seen in Figure 6, enabling it to be used as a toilet seat and has a parallel forwardly and rearwardly extending bars 45 of angle iron secured to its under side for slidably and demountably supporting a pot or receptacle 46 on the under side of the sub-bottom 36 and beneath the opening 44, as illustrated in dotted lines in Figure 5. A stop 47 may be provided on the under side of the sub-bottom 36 to limit the extent that the receptacle 46 can be inserted on the supporting angle irons 45, from rear to front, and so that said receptacle will be directly beneath the opening 44 when advanced into engagement with the stop 47.

The bottom 35 which is removably supported on the sub-bottom 36 and removed when said sub-bottom is utilized as a toilet seat, is provided

with a notched forward edge 48 to engage the post 39 and has laterally extending lugs 49 for engagement between the front corner posts 37 and the adjacent uprights 38. Said lugs 49 and the notch 48 combine to normally retain the seat or bottom 35 correctly positioned on the sub-bottom 36 and with the rear edge of the bottom 35 engaging against the back rest 41.

A cleat 50 is secured to the under side of the tray 26 and extends between the sides 16. Two contractile coiled springs 51 are suspended from the cleat 50 by eye fastenings 53. The lower ends of the springs 51 are connected to similar eye fastenings 52 which are anchored to and rise from the rail 40 adjacent the front corner posts 37. An angle bracket 54 has an apertured leg which is fastened to each of the sides 16 at the rear edge and adjacent the upper end thereof. Said angle brackets 54 are each provided with an inwardly extending leg which is disposed beneath the rear portion of the tray 26 and which extends into the notch 28 thereof and has an eye 55 in its under side and at its inner end to which is anchored an end of a contractile coil spring 56. The depending ends of the springs 56 are connected by eye fastenings 57 to the rail 40 adjacent the two rear corner posts 37 and cooperate with the springs 51 to yieldably support the chair structure 34 beneath the notched portion 28 of the tray 26 and for vertically yielding movement with respect thereto. It will also be readily apparent that the springs 51 and 56 will permit the chair structure 37 to swing forwardly or rearwardly or laterally with respect to the remainder of the article of furniture 10.

A rigid brace member 58 is pivotally connected at one end thereof to the rear edge of each of the sides 16. Said braces 58 are each provided adjacent its free end with a laterally opening notch to form a downwardly opening hook 59 when the brace 58 is swung inwardly and upwardly to substantially a horizontal position, as illustrated in dotted lines in Figure 3. The hooks 59 are adapted to engage headed studs 60 which project rearwardly from the rear corner posts 37 so that the braces 58 will maintain the seat structure 34 substantially stationary with respect to the remainder of the article of furniture 10 when in engagement with the studs 60 to thereby render the seat structure immobile for use as a toilet seat or when the item of furniture is being utilized as a high chair for feeding an infant or young child. However, when the braces 58 are disengaged from the studs 60 and disposed in their normal depending positions, the child may swing in the seat structure or bounce up and down therewith relatively to the remainder of the structure 10. Thus used, the child may place its feet upon the floor surface as provided by the partition 18 or younger children may utilize the foot rest 32. A hand rail 61, of circular cross section is disposed above the tray 26, forwardly of the notch 28 and is supported by uprights 62 at its ends which rise from the tray 26.

From the preceding detailed description of the furniture structure 10, the various uses thereof will be readily apparent and it will be obvious that such structure provides a combination item of furniture for use by infants and young children ranging in age from approximately five months to two years and which may be utilized as a high chair for feeding the child, a toilet seat, a swing and also a play pen. The chest 21 also affords a convenient compartment for

the storage of the child's toys or play things, not shown. The seat structure 34, as previously described, affords a structure which is extremely safe as it positively prevents the child from climbing or falling out of the seat when the back 5 48 is latched in a closed position.

Various modifications and changes are contemplated and may obviously be resorted to, without departing from the spirit or scope of the invention as hereinafter defined by the appended claims.

I claim as my invention:

1. A combination article of furniture for infants and young children comprising an upright supporting structure including a tray disposed in an elevated position, said supporting structure having an open rear side, a seat structure supported within said supporting structure beneath said tray, said tray having a notch disposed above the seat structure and adapted to accommodate the upper portion of the body of a baby or small child supported in the seat structure, said notch having an end opening outwardly of the rear edge of the tray and of the open rear side of the supporting structure, said seat structure including a back rest extending upwardly therefrom through the tray notch, said back rest being hinged along one upright edge thereof to a side of the seat structure to swing rearwardly for exposing the back of the seat structure and the open end of the notch.

2. An article of furniture as in claim 1, a portion of the seat structure including the back rest being disposed in the open rear side of the supporting structure, and latch means carried by the back rest and releasably latching the other upright edge of the back rest to a part of the seat structure for closing the back of the seat structure and the open end of the notch.

3. An article of baby furniture comprising an upright supporting structure having an open rear side and a top wall defining a tray, said top wall having a notch opening outwardly of one edge thereof and toward the open rear side of the supporting structure, a seat supported by

5

the supporting structure beneath the tray notch including a back rest extending into the tray notch and normally closing the open end thereof, said back rest being hinged at one side edge thereof to a part of the seat structure to swing outwardly of the open rear side of the supporting structure to expose the back of the seat and the open end of the notch, and latch means carried by the back rest and releasably latching the back rest at its other upright edge to a part of the seat to retain the back rest in a position for closing the back of the seat and the open end of the notch.

15 4. An article of baby furniture comprising an upright frame having an open rear side, said frame including a top wall defining a tray having a notch opening into said open rear side, a seat supported in the frame beneath the tray having an open end facing the open rear side of the frame, a back rest normally closing the open end of the seat and extending upwardly into the notch and normally closing the open end thereof, said back rest being swingably connected to the seat for swinging movement outwardly through the open rear side of the frame to expose the open end of the seat and the open end of the notch.

25 5. An article of baby furniture as in claim 4, and means yieldably supporting the seat in the frame for reciprocating movement toward and away from the tray and for swinging movement relatively to the frame and tray.

IDA E. ADAMS.
